1,021,780. FIREPROOF FLOOR CONSTRUCTION FOR BUILDINGS. ERNEST V. JOHNSON, Chicago, Ill. Filed Jan. 7, 1910. Serial No. 536,801.

To all whom it may concern:

Be it known that I, ERNEST V. JOHNSON, a citizen of the United States, residing in Chicago, in the county of Cook and State of Illinois, have invented a new and useful Improvement in Fireproof Floor Construction for Buildings, of which the following is a specification.

My invention relates to improvements in fireproof floor construction for buildings.

The object of my invention is to provide an improved fireproof floor construction, which will embody in a single unitary structure, all the merits and advantages of the best or most approved reinforced concrete construction, without any of its disadvantages or defects, and also all the merits and advantages of the best or most approved terra cotta or tile work construction without any of the defects or disadvantages incident or supposed to be incident thereto, and which at the same time will be capable of being rapidly and cheaply built.

My invention consists in the novel construction of parts and devices, and in the

novel combinations of parts and devices herein shown and described, and by which this object or result is practically accomplished, the same being more particularly set forth in the claims.

In the accompanying drawing forming a part of this specification, Figure 1 is a plan view, partly in horizontal section, of a combined reinforced concrete and terra cotta or tile-work, fire-proof floor construction embodying my invention. Figs. 2 and 3 are vertical sections on lines 2-2 and 3-3 respectively of Fig. 1. Fig. 4 is a detail, partial plan view showing the terra cotta or tile-work and the tensile acting metal members or reinforcing rods in place, ready to receive the concrete. Fig. 5 is a detail cross section of the panel tile.

In the drawing, A represents the steel posts or upright frame members of the building; B the horizontal steel beams or girders of the building framework; C the tensile acting or reinforcing members, preferably steel rods crossing each other at right angles and extending over or anchored to the girders B; D hollow or panel tile, preferably twelve inches square, and of such depth as the floor load and clear span may require, arranged in longitudinal and transverse rows in the spaces between the reinforcement members C and with their hollows d extending in the same direction; E, slab or spacer tile, preferably about one inch thick and three inches wide, and arranged in rows between the sides d¹ of the panel

tile D; F, U-shaped or channel tile, arranged in transverse rows between the ends d² of the panel tile D, and closing by their upright sides f, the openings d of the panel tile, each channel tile being preferably twelve inches long by about five inches wide, and corresponding in height or depth to the height or depth of the panel tile D, the interior space between the upright sides f of each channel tile being preferably three inches, and thus corresponding in width to the slab or spacer tile E, and thereby forming a network of continuous and connected narrow open spaces for reception of the steel rods or reinforcement members C, and the series of crossing solid concrete beams or ribs G in which the reinforcement members C are embedded, and which fill the narrow longitudinal spaces between the upright sides of the panel tile D and the narrow transverse spaces between the upright sides of the channel tile; and II non-combustible heat insulating members, preferably of mineral wool, asbestos, cork or other equivalent material interposed between the steel rods or reinforcement members C and the slab or flat spacer tile E and bottom webs f¹ of the channel tile F.

The tension or reinforcement members C preferably extend continuously from one side or the wall of the building to the opposite side or wall thereof, and the same are anchored in the concrete beams or ribs G throughout their entire length. At their ends the steel reinforcements C are anchored in the steel girders of the outer wall, if the outer wall contains steel girders, and if not, they are suitably anchored in the masonry of the outer walls.

The solid concrete beams or ribs G are uniformly spaced and cross each other at right angles in a solid integral network, both the longitudinal series G¹ and the transverse series G² extending between the girders which form the rectangular floor unit, bay or panel B¹ bounded by the steel girders B or by the outer masonry walls, as the case may be. The solid, integral concrete beams or ribs G, in connection with their steel reinforcements C transmit the stress to the four sides of the floor unit, bay or panel B¹, whether such floor unit, bay or panel is supported on its four sides by steel girders B, or on one or more sides by a brick or other masonry outer wall.

The spaces between the solid integral concrete ribs or beams G are formed by the hollow or panel tile D, the same being preferably in units, twelve inches square, and of such depth as may be required to safely support the superimposed load, the depths of the panel tile D and channel tile F being proportioned to the length of the clear span between the girders or other supports bounding each floor unit, bay or panel B¹.

The hollow or panel tile D are separated from each other by the transversely extending channel tile F which are set in place in cement mortar f^3 , the upright sides f of the channel tile being of the same depth as the intermediate hollow or panel tile D, and being laid against the open ends of the same, serve to close up the hollow spaces d in the panel tile D.

The longitudinally extending concrete ribs or beams G are gaged to uniform size, preferably about three inches in thickness horizontally, by the slab or spacer tile E which are laid flat on portable centering, and against the edges of which the closed sides d^1 of the hollow tile abut, and against which the ends of the transversely extending channel tile F also abut. By this arrangement, the hollow or panel tile D are uniformly spaced in both directions; in one direction, by the slab or spacer tile E, and in the other direction by the channel tile F, and opportunity is thus afforded for the introduction of such form of reinforcing members or tensile acting members C as may be most suitable. The steel reinforcements C which are intended to take up the tension stress in the floor unit, bay or panel between

girders, extend continuously in longitudinal and transverse directions crossing each other at right angles and are carried over the intermediate girders B into the adjoining floor units, bays or panels. Opportunity is thus afforded to obtain the equivalent of continuous beams extending from outer wall to outer wall of the building or structure. One or more steel reinforcements C may be used in each of the concrete beams or ribs G, depending on the amount of tensile stresses developed by the known floor load which the structure may be called upon to support.

After the 12x12 hollow or panel tile D are set in place on the portable centering in the manner above described, being spaced in one direction by the longitudinally extending slab or spacer tile E, and in the opposite direction by the channel tile F, and the steel reinforcements C have been laid in position transversely and longitudinally in the continuous channels or spaces formed by the sides of the panel tile and by the channel tile, liquid Portland cement concrete is poured in and thoroughly tamped around the steel reinforcements C, and filled up flush with the top surface of the tile D, F. This method and arrangement assures perfection of workmanship, especially in relation to the solid, continuous, integral concrete beams or ribs G and the steel reinforcements C embedded therein throughout their entire length or surface. The hollow ends of the panel tile D being sealed up by the cement joint f^3 between the upright sides f of the channel tile F and the ends d^2 of the floor

tile, prevents the loss of any cement or concrete by escape into the hollows d of the tile D; and only the actual amount of concrete required to fill the spaces between the tile D D and between the upright sides of the channel tile is thus required. It would be a disadvantage, should any of the Portland cement concrete filling escape into the hollow cavities d of the tile D, for the reason that it would be of no use in compressive strength and would entail an excess cost of construction and add materially to the dead weight of the floor, without any structural compensation or increased strength.

It will be observed that by the above described construction and combination of hollow panel tile with slab or spacer tile and channel tile, I provide for the protection of all the steel reinforcements C with at least an inch or more of fireproof material on the under side, while at the same time, the underside portion of the floor which forms the ceiling for the story below, presents a uniform and continuous tile surface for reception of plastering, the underside or ceiling surface being in part formed by the bottom webs d^1 of the panel tile D, in part by the slab or spacer tile E and in part by the bot-

tom webs f^1 of the channel tile F. This is a great advantage over previous constructions wherein tile are used in connection with concrete as a floor construction. Where the underside or ceiling side of the floor construction is composed in part of tile and in part of concrete, great inequality in the plastering results, as well as additional expense, labor and difficulty in applying the plastering, as the variation in the suction due to different degrees of dryness and porosity or density of the tile portion and concrete portion causes the plastering to stain through, making the ceilings unsightly a few weeks after they are finished, and often also causes cracking or other disfigurement of the plastering.

By my construction and combination of panel tile, channel tile, slab or spacer tile, integral solid crossing concrete beams or ribs and steel reinforcements, it is possible to compute accurately the stresses on the reinforcements in every direction, and produce a monolithic floor unit or slab of uniform strength. My fireproof floor construction is also superior to existing floor arch constructions for the reason that in my construction, equal distribution of the tensile acting steel reinforcing members in all directions, ties the structure rigidly together, and greatly increases its strength to resist impact from falling material or contents which might be stored in the building and be partially consumed during a fire. My improved construction also affords most efficient resistance to earthquake shocks or

wind pressure stresses in high buildings.

After the floor construction, as above described, is completed and in place, and the false work used as temporary supports in the construction of the floor, removed, the top surface thereof is either finished with a Portland cement wearing surface K, or with wood flooring M, nailed to floor strips M¹ in the usual manner. In cases where a Portland cement finished floor is applied directly to the top surface of the panel tile D and concrete ribs or beams G, additional compressive value is thereby given to the construction for the reason that the natural affinity between the tile and Portland cement assures a perfect bond between the two materials after the cement finish has thoroughly set. The addition of the Portland cement finished surface K on top of the tile justifies computing an increased value to the strength of the floor proportionate to its increased depth, providing a sufficient quantity of metal is added to the reinforcement members C to correspond to such increased depth of the floor.

The non-combustible heat insulating members, H, of asbestos, mineral wool or other heat insulating non-combustible material,

are preferably about an inch in thickness, and are interposed between the steel reinforcements C and the slab or spacer tile E, and also between the bottoms of the channel tile F and such steel reinforcements. The object of the heat insulating members H is to protect the steel reinforcements from expansion during an extreme fire acting directly on the soffit of a floor construction. Recent fire tests have demonstrated the necessity for properly insulating steel reinforcements when bedded in concrete or otherwise protected. Fire insurance experts generally require at least two inches thickness of concrete below the outer or lower edge or surface of all steel reinforcements in floor slabs, panels or units that take up tensional stress. I have found by practical demonstration that a fire of one thousand degrees Fahrenheit will permeate two inches of Portland cement concrete to such an extent during one hour's fire, that the expansion of the steel reinforcement by the heat will be sufficient to seriously damage monolithic concrete floor slabs. I overcome this difficulty by the non-heat conducting or insulating members H of asbestos, mineral wool, cork or other equivalent material. The slab or spacer tile E may be provided with a groove or channel on their upper surfaces to receive and retain in position the non-heat conducting, non-combustible insulating members H.

N represents the plastering on the under side or ceiling surface of my floor construction.

P P¹ are insulating or filler members sur-

rounding and protecting the lower portions of the steel girders B.

While I have herein shown and described the preferred construction of my invention, and the best means known to me for practicing the same, it will of course be understood that certain features of my improved floor construction may be employed and others omitted.

To afford a stronger bond or union between the concrete members G and the tile D, F, the tile may be furnished with dovetail grooves $d^4 f^4$. In cases where the cement finish or floor surface K is employed, the wood floor strips M¹ and wood flooring M are omitted.

I claim:

1. In a fireproof floor construction, the combination with supporting girders, of hollow panel tile having open ends and spaced apart longitudinally and transversely and arranged in longitudinal and transverse rows, transversely extending channel tile arranged transversely between and closing the ends of said hollow panel tile, spacer slab tile extending between the longitudinal rows of hollow panel tile and

between the ends of said channel tile, longitudinally and transversely extending solid integral concrete beams or ribs filling the channels of said channel tile and the longitudinal spaces between said hollow panel tile, and crossing steel reinforcements extending longitudinally and transversely and embedded in said concrete beams or ribs, substantially as specified.

2. In a fireproof floor construction, the combination with supporting girders, of hollow panel tile having open ends and spaced apart longitudinally and transversely and arranged in longitudinal and transverse rows, transversely extending channel tile arranged transversely between and closing the ends of said hollow panel tile, spacer slab tile extending between the longitudinal rows of hollow panel tile and between the ends of said channel tile, longitudinally and transversely extending solid integral concrete beams or ribs filling the channels of said channel tile and the longitudinal spaces between said hollow panel tile, and crossing steel reinforcements extending longitudinally and transversely and embedded in said concrete beams or ribs, and non-heat conducting and incombustible insulating members interposed between said steel reinforcements and said spacer slab tile and the bottom webs of said channel tile, substantially as specified.

3. In a fireproof floor construction, the combination with hollow panel tile having open ends and spaced apart longitudinally and transversely and arranged in longitudinal and transverse rows, channel tile extending transversely between and closing

1021780 994

the hollows of said panel tile, a network of longitudinal and transverse concrete ribs filling said channel tile and the spaces between the sides of said panel tile, and tensile acting reinforcements for said concrete ribs, tile members below said tensile acting reinforcements and heat insulating members interposed between said reinforcements and the tile members therebelow, substantially as specified.

4. In a fireproof floor construction, the combination with hollow panel tile having open ends and spaced apart longitudinally and transversely and arranged in longitudinal and transverse rows, channel tile extending transversely between and closing the hollows of said panel tile, a network of longitudinal and transverse concrete ribs filling said channel tile and the spaces between the sides of said panel tile, and tensile acting reinforcements for said concrete ribs, tile members below said tensile acting reinforcements said reinforcements extending both longitudinally and transversely, and heat insulating members interposed between said

reinforcements and the tile members therebelow, substantially as specified.

5. In a fireproof floor construction, the combination with supporting girders, of hollow panel tile having open ends and spaced apart longitudinally and transversely and arranged in longitudinal and transverse rows, transversely extending channel tile arranged transversely between and closing the ends of said hollow panel tile, spacers of slab tile at the intersection of the longitudinal and transverse spaces between the rows of tile, said spacers lying between the ends of said channel tile, longitudinally and transversely extending solid integral concrete beams or ribs filling the channels of said channel tile and the longitudinal spaces between said hollow panel tile, and crossing steel reinforcements extending longitudinally and transversely and embedded in said concrete beams or ribs, substantially as described.

ERNEST V. JOHNSON.
